UNITED STATES PATENT OFFICE

MASA FUJITA, OF SAKAI-GUN, FUKUI, JAPAN

DEFORMABLE CHAIR

Application filed September 13, 1928. Serial No. 305,699.

The invention relates to improvements in deformable chairs, particularly those employed in connection with medical examination.

5 According to the invention the main parts of the deformable chair consist of a seating unit upon which a patient may sit with his or her feet resting upon the foot rest, the legs depending along the leg support, and a leaning unit against which the patient may rest his or her back. The seating and the leaning units are operably connected by means of a transmission gear on the one hand and by means of a link mechanism on the other hand 10 in such a manner that the sitting and the leaning units may be rotated differentially, or the whole device may assume a collapsed lying position. The link mechanism is constructed in such a way that it does not obstruct the 15 free rotation of the seating and the leaning units.

With the aid of my invention, it will be possible to interconnect the seating and the leaning units in such a manner that when 20 the body of the patient, together with the seating unit in an upright position, is rotated through 180°, the chair back will rotate through half that amount, exposing the back of the patient for unobstructed examination.

25 In the accompanying drawings, which show one embodiment of the invention:

Figure 1 is a side elevation, part of the control casing being broken away,

Figure 2 is a plan thereof,

Figure 3 is a side elevation of the seating and the leaning units as extended to a collapsed lying position, a part of the pedestal being broken away,

Figure 4 is a bottom view thereof, the control casing being partly broken away,

Figure 5 is an elevation, on a somewhat enlarged scale, of the transmission gear connecting the seating and the leaning units, the seat proper being shown in elevation and parts being shown in vertical section on line V—V of Figure 6,

Figure 6 is a plan of the transmission gear,

Figure 7 is a bottom plan of the chair when 50 the seating and the leaning units have been

rotated differentially to enable unobstructed examination of the back of the patient,

Figure 8 is a diagram explaining the motion of the link mechanism connecting the two units. 55

Referring more particularly to the numerals of reference on the drawings, 1 is the seat proper of the deformable chair. Solidly attached to the seat 1 is a vertical shaft 2, by means of which the seat is rotatably mounted 60 on a pedestal 3, resting on a ball bearing 4. The seat proper is not entirely circular but is enlarged laterally, as at 5, at the front part thereof to form a rectilinear edge, at which part the leg support 6 is hinged, as at 65 7. At the lower end of the leg support, a foot rest 8 is hinged, as at 9. The seat proper 1, the leg support 6 and the foot rest 8 constitute the seating unit of the chair.

Rotatably mounted on the pedestal 3 is a 70 covering disc 10, to which is hinged, as at 11, the chair back 12. The chair back 12 in combination with the covering disc 10 constitute the leaning unit of the chair.

With a view to adjust the back 11 to any 75 desired inclination in regard to the seat proper which is always in parallel relation to the covering disc, the latter is formed with a toothed arcuate or curved portion 13 on

which engages a pawl 14 which is suitably pivoted on the control casing 15 provided at the rear side of the chair back and acted upon by a spring 16. The pawl 14 may be controlled by the handle 17 through a suitably disposed lever connection 18. By this means the inclination of the chair back can be varied at will. 80

To move the leg support 6 and the foot rest 8 in conformity and in cooperation with the chair back, the casing 15 is extended to 90 form a bar 19 at the end of which one end of a link 21 is hinged at 20. The link 21 is shaped like an oblong ellipse encircling the pedestal 3 and is formed at the other end with a semi-circular horizontal groove 22, in which slidably engages the end of a horizontal arm of a bent lever 23 which is pivoted at the extremity 24 of a bracket 25 rigidly attached to the leg support 6. The other end 26 of the bent lever 23 is connected to a connect- 95 100

ing rod 27, the other end 28 of which is in turn connected to a bracket 29 rigidly attached to the foot rest 8.

In the link connection, the hinge points 20 and 24 of the link 21 and the bent lever 23 respectively form, together with the hinge points 7 and 11 of the leg support and the chair back respectively, a parallelogram (Fig. 9). Also the hinge points 24, 26, 28 and 9 form a parallelogram. Therefore, the link 21, together with the arm of the bent lever 23 engaging therewith, always moves horizontally, and consequently the foot rest 8 will always assume a horizontal position regardless of whether the chair is in an upright position shown in Figure 1 or in a collapsed position shown in Figure 4 or in any intermediate position.

Within the covering disc 10 underneath the seat 1 and keyed to the vertical shaft 2 of the seat is a gear wheel 30. This gear wheel 30 is operably connected with an annular gear wheel or ring gear 31 through the intermediary of two pairs of intermeshing pinions 32, 33 provided on an arm 34 fixed to the pedestal 3. The ring gear 31 has along the outer circumference thereof a series of notches 35, so that it also constitutes a ratchet wheel to cooperate with a coupling pawl 36 pivoted to the covering disc 10. The coupling pawl 36 may be controlled by means of a handle 37 and a lever 38.

When the coupling pawl 36 is caused to engage one of the notches 35, the seating unit 35 is brought into operating engagement with the leaning unit, so that when either one of the two units, the seating unit for example, is rotated 180° in either direction, the leaning unit will rotate in the same direction through half that amount, or 90°, so that if the patient, after his or her breast has been examined at a position of the chair shown in Figure 1, is turned through 180°, the parts will assume the position shown in Figure 7, exposing the patient's back for unobstructed examination.

If the coupling pawl is caused to engage with one of the indentations 39 (Figure 5) formed in the underside of the seat 1 along the periphery thereof, the seating and the leaning units will be simply connected to each other and the two will rotate together as a whole on the pedestal. If the coupling pawl is brought to an intermediate neutral position engaging with neither the seat 1 nor the annular wheel 31, the two units will be entirely free to rotate independently of each other.

With the object of holding the depending parts 6 and 8 firmly in the upright position of the chair, I have provided a pair of brackets 40 fixed to the seat proper 1 adjacent the hinge points 7. 41 is a pillow for the head of the patient to lean on.

15 What I claim is:

1. A chair comprising a pedestal; a unit rotatably mounted on the pedestal and including a seat, a leg support and a foot rest; a second unit rotatably mounted on the pedestal and including a chair back; and a set of intermeshing gears connecting the unit including the seat with the unit including the chair back to transmit the movement of either unit to the other. 70

2. A chair comprising a pedestal, a seat rotatably mounted on the pedestal, a leg support hinged to the seat, a foot rest hinged to the leg support, a disc-like member rotatably mounted on the pedestal, a chair back hinged to the disc-like member, a link connection between the chair back and the leg support and the foot rest, and means to control the inclination of the chair back, the leg support and the foot rest simultaneously, relatively to the seat; the said link connection comprising an oblong elliptical member 85 encircling the pedestal. 80

3. A chair comprising a pedestal, a seat rotatably mounted on the pedestal, a leg support hinged to the seat, a foot rest hinged to the leg support, a disc-like member rotatably mounted on the pedestal, a chair back hinged to the disc-like member, means for operably connecting the disc-like member with the seat, a link connection between the chair back and the leg support and foot rest, and means to control the inclination of the chair back, the leg support and the foot rest simultaneously, relatively to the seat; the said link connection comprising an oblong elliptical member 100 encircling the pedestal, and a bent lever having one arm thereof engaged with the said elliptical member and the other arm engaged with a connecting rod connected to a bracket fixed to the foot rest. 90

4. A chair, comprising a pedestal; a unit rotatably mounted on the pedestal and consisting of a seat, a leg support and a foot rest; a chair back having a separate rotatable mounting on the pedestal for rotation independently of and relatively to said seat unit; and means for operatively connecting said chair back and seat unit together to transmit the movement of either element to the other. 110

5. A chair, according to claim 4, in which 115 the means for connecting together the chair back and the unit including the seat comprises an annular member provided with a peripheral series of notches, a connection between said member and one of the two elements to be rotated, and a pawl for interchangeable engagement in said notches carried by the other element. 120

6. A chair, according to claim 1, in which 125 the set of intermeshing gears comprises a gear fixed to the seat, an annular gear encircling the seat gear, and a pair of intermediate gears meshing with each other and with the seat gear and annular gear, thereby to ob- 130

tain a differential movement as between the seat and the chair back.

7. A chair, comprising a pedestal; a unit rotatably mounted thereon and consisting of a seat, a leg support and a foot rest; a second unit rotatably mounted on the pedestal and including a chair back; and differential gearing operably connecting the two units to obtain a differential movement as between the seat and the chair back.

10 8. A chair, comprising a pedestal; a seat rotatably mounted thereon; a leg support hinged to the seat; a covering disc rotatably mounted on the pedestal below said seat; a chair back hinged to said seat; and a link connection between the chair back and the leg support embodying an oblong elliptical member encircling the pedestal.

15 9. A chair, comprising a pedestal; a seat rotatably mounted thereon; a leg support hinged to the seat; a covering disc rotatably mounted on the pedestal below said seat; a chair back hinged to said seat; and a gear connection between the seat and the covering disc and its associated chair back for obtaining 20 a differential rotary movement between said seat and back.

25 10. A chair, comprising a pedestal; a seat rotatably mounted thereon and having a leg support associated with it; a covering disc rotatably mounted on the pedestal below said seat; a chair back attached to said seat; a gear fixed to said seat; a loose annular gear encircling the first gear; intermediate gears carried by the pedestal in mesh with each 30 other and with the first gear and the annular gear; and a device for releasably coupling said annular gear to said disc.

35 11. A chair according to claim 10, in which the annular gear is provided with a peripheral series of notches; and in which the coupling device comprises a pawl pivoted to the disc and engageable in said notches.

40 In testimony whereof I affix my signature.
45 MASA FUJITA.
